UNITED STATES PATENT OFFICE.

JAMES W. BOYD, OF EAST LIVERPOOL, OHIO.

INTERNAL-COMBUSTION ENGINE.

Application filed April 13, 1926. Serial No. 101,717.

This invention relates to improvements in internal combustion engines and has reference more particularly to an improved rotary combustion chamber and valve mechanism of such engine.

One of the important objects of the present invention is to provide an internal combustion engine wherein the rotary member is provided with two combustion chambers 10 for each cylinder, suitable means being provided for expelling or exhausting all of the burnt gases from one of the combustion chambers while a fresh incoming charge will be delivered to the other combustion 15 chamber, which will be cleared of all burnt gases.

Another important object of the invention is to provide an internal combustion engine of the above mentioned character wherein 20 the rotary combustion chamber and valve mechanism during its travel performs the function of inlet and exhaust valves, the combustion chambers being arranged at substantially right angles with respect to each 25 other, yet not communicating with each other.

A still further object is to provide an internal combustion engine of the above mentioned character which is simple in construction, inexpensive, and furthermore adapted 30 to the purposes for which the same is designed.

Other objects and advantages of this invention will become apparent during the 35 course of the following description.

In the accompanying drawing forming part of this specification, and in which like numerals are employed to designate like parts throughout the same:—

40 Figure 1 is a side elevation showing an internal combustion engine, embodying my improved rotary combustion chamber and valve mechanism, parts of the engine being shown in section.

45 Fig. 2 is a view partly in elevation and partly in section of the head.

Fig. 3 is an enlarged fragmentary sectional view through the rotary combustion chamber and valve member showing the arrangements of the ports formed therein.

50 Fig. 4 is a sectional view taken on line A—A of Figure 1 showing the rotary combustion chamber and having one of its passages or chambers in registry with the adjacent intake ports, the piston in the cylinder being shown at the beginning of its intake

stroke, and the rotary combustion chamber member rotating in the direction indicated by the arrow.

Fig. 5 is a similar view showing the position of the piston in the cylinder and the top of the compression stroke.

Fig. 6 is a similar cross sectional view showing the piston at the end of the power stroke and the combustion chamber and valve member being rotated so the exhaust ports will communicate, and

Figure 7 is a detail showing the arrangement of the several ports formed in the head.

In the drawings, wherein for the purpose of illustration is shown the preferred embodiment of my invention, the numeral 1 designates generally an engine block and bolted or otherwise secured thereto is the 75 head 2. The head as well as the blocks are provided with the usual water jacket in the manner well known in the art. In the present instance, I have shown the invention in conjunction with a six cylinder engine of the 80 four-cycle type, but it is to be understood of course, that the invention is equally applicable to engines having either a greater or less number of cylinders.

The head 2 is provided with a series of fuel 85 intake and exhaust ports designated by the numerals 3 and 4 respectively and a construction and arrangement of these ports are more clearly shown in Figs. 2, 4, 5 and 6 of the drawings. The head 2 is further provided with an additional series of intake ports such as is shown at 5 with reference 90 more particularly to Figs. 4, 5 and 6 of the drawings. The head 2 is further provided with the air exhaust ports 6 and 7 95 respectively, and the purpose thereof will also be hereinafter more fully described.

The head 2 is provided with the longitudinally extending circular bore 8 and adapted to be mounted therein is the rotary combustion chamber and valve member designated generally by the numeral 9. The bottom of the head 2 is provided with a series of openings 10 which afford communication between the bore 8 of the head and the upper ends of 105 the respective cylinders 11 and mounted in the top of the head 2 directly in line with the respective openings 10 are the spark plugs 12.

The rotary combustion chamber and valve member 9 comprises a substantially solid cylindrical member at the ends of which are formed suitable trunnions 13 adapted for ro-

tation in suitable bearings 14 provided therefor at the respective ends of the head 2.

The rotary combustion chamber and valve member 9 is actuated through the medium of an operative connection between one of the trunnions and one end of the usual crank shaft 15 in the present case, such an operative connection is illustrated by way of a train of intermeshing gears designated generally by the numeral 17. The gear ratio is one to eight, that is to say, the crank shaft will rotate eight times while the rotary member is completing a single revolution. It is however, to be understood that I do not wish to limit myself to the particular manner in which the rotary valve is connected to the crank shaft.

The solid cylindrical member forming the rotary valve and combustion chamber member is further provided with the annular oil distributing groove or channel 18, whereby the rotary combustion chamber and valve member will be properly lubricated and the provision of these lubricating channels in the rotary valve is clearly shown in Fig. 1.

The rotary combustion chamber and valve member 9 is provided with a pair of passages 19 and 20 respectively in each cylinder as is clearly shown in Fig. 3, the passages or openings in each cylindrical member comprising the rotary combustion chamber and valve member and are disposed at right angles to each other and furthermore do not communicate with one another. These transversely extending passages or openings are each formed in the rotary combustion chamber and valve member cooperating in conjunction with the several parts in the engine head and adapted to act as or provide alternate combustion chambers. It is of course to be understood that the rotation of the rotary member in regard to the movement of the piston 21 in the respective cylinders is timed so that all of the parts will properly function at a predetermined time.

In Fig. 4 of the drawings, the passage or opening 19 is in communication with the intake port 3 formed in the head 2 for admitting the charge to a cylinder as the piston 21 is about to start downwardly on its stroke. Also, the passage or opening 19 will be in registry or communication with the additional intake 5 formed in the head 2 at a point diametrically opposite the intake 3 through provision of the additional intake or inlet port to properly mix the air in the combustion chamber incoming charge. However, additional inlet ports may be eliminated if not desired.

In Fig. 5 of the drawings, the piston is shown at the top of the compression stroke for the ignition, the passage 20 being in communication with the air inlet and exhaust ports 6 and 7 respectively, whereby a supply of air under pressure is admitted for the pur-

pose of cleaning out all of the burnt gases from the combustion chamber. The air may be supplied from a suitable source.

In Fig. 6, the piston has completed its entire stroke and passage 19 formed in the rotary combustion chamber and valve member 9 is moving out of registry with the opening 10 formed in the bottom of the head 2 and which affords communication with the cylinders of the engine, and the passage 19 is in the act of being brought into registry with the exhaust port 4. One of the passages will be cleared of burnt gases while the passage disposed at right angles thereto is functioning as an active combustion chamber.

For the purpose of facilitating the removal of carbon which may collect in the top of the cylinders, or on top of the pistons, I provide suitable openings 22 in the sides of the several cylinders adjacent the top thereof and suitable screw plugs 23 are removably fitted in these openings. This feature is more clearly illustrated in Figs. 4, 5 and 6 of the drawings.

The provision of the air inlet and exhaust ports 6 and 7 respectively provides a means whereby the burnt gases may be easily and completely expelled from the combustion chambers so as to insure the supply of a fresh charge to the several cylinders of the engine, thus aiding in quick starting of the motor thereby tending to increase the efficiency of the operation of the motor.

While I have shown the preferred embodiment of my invention, it is to be understood that various changes in the size, shape and arrangement of parts may be resorted to without departing from the spirit or sacrificing any of the advantages of the appended claims.

Having thus described my invention, what I claim as new is:—

1. In an internal combustion engine, a cylinder head having inlet and exhaust ports, and a rotary member arranged in said head and provided with passages forming combustion chambers adapted for cooperation with the aforementioned ports, said passages being arranged at right angles with respect to each other and being disposed in non-communicating relation.

2. In an internal combustion engine, a cylinder head having inlet and exhaust ports, and a rotary member arranged in said head and provided with passages forming combustion chambers adapted for cooperation with the aforementioned ports, said passages being arranged at right angles with respect to each other and being disposed in non-communicating relation, the passages alternately receiving a charge and being cleared of burnt gases.

3. In an internal combustion engine, a cylinder head having inlet and exhaust ports, and a rotary combustion chamber member

arranged in the head, said member having non-communicating passages formed therein, the passages being disposed at substantially right angles with respect to each other 5 and adapted for cooperation with the afore-mentioned ports in said head, the burnt gases in one of the passages or combustion chambers being expelled therefrom when one of the passages in the rotary combustion chamber 10 member is in communication with the inlet and exhaust ports in the head.

4. In an internal combustion engine, a cylinder head having inlet and exhaust ports, an air inlet and exhaust port, and a rotary 15 combustion chamber member arranged in the head, said rotary combustion chamber member having non-communicating passages

formed therein, said passages being disposed at substantially right angles with respect to each other and adapted for cooperation with 20 the afore-mentioned ports in said head, the burnt gases in the combustion chamber being expelled therefrom when one of the passages in the rotary combustion chamber member is in communication with the inlet 25 and exhaust air ports in said head, said head being further provided with an additional port disposed at a point diametrically opposite the gas inlet port and cooperating therewith. 30

In testimony whereof I affix my signature.

JAMES W. BOYD.
